N° 847
Charles Müller's Design for a Statuette of Burton
as Captain Cuttle.

Patented Octo. 21. 1856.

Des. 847

Charles Müller of New York N.Y.
Letters Patent No. 847 Dated Oct 21st 1856

To the Schedule referred to in these Letters Patent and making part of the same.

To all whom it may concern: Be it known that I Charles Müller of the City, County and State of New York have invented or produced a new design for a Statuette of Mr. Burton as "Captain Cuttle" in the drama of Domley & Son; and I do hereby declare that the following is a full, clear, and exact description of the same reference being had to the accompanying drawing forming part of this specification.

This design, as will be seen from the drawing, represents Mr. Burton as standing the whole body being very slightly inclined backward, the weight resting on the left leg; the right foot slightly advanced so as to bring the heel as far forward as the instep of the left foot, the toes rather more turned out than the left foot, the leg a little bent by the knee being brought forward.

Under the left arm he holds a tarpaulin hat, supported by the fingers of the left hand from the lower side of the crown, the brim of the hat pressed closely against the left side of the body.

The right arm from the shoulder to the elbow hangs by his side the elbow crooked so as to present the lower part of the arm at nearly a right angle with the upper. - The right hand has been cut off and shows only the stump of the wrist which is furnished with a pocket and hook. The head is slightly inclined towards the right shoulder, bald on the top, with a profusion of hair on the sides and back. — Costume. Shirt with plaited bosom, high collar, right side turned down, left side standing up; Cravat, loosely tied in double bow, with ends rather long; double breasted vest, with rolling collar; pea jacket, collar and flaps turned back so as to show a large portion of the vest, pantaloons, rather loose; low pump shoes, square-toed. — The whole representing an elderly gentleman of rather portly figure.

What I claim as my invention and desire to secure by Letters Patent, is

The Design herein described and shown for a Statuette of Mr. Burton as "Captain Cuttle".
